CLAIM

The ornamental design for a medical computer, as shown and described.

DESCRIPTION

FIG. 1 is a perspective view of the medical computer showing my new design;

FIG. 2 is a front view thereof;

FIG. 3 is a left side view thereof;

FIG. 4 is a top view thereof, the bottom view being unornamented;

FIG. 5 is a right side view thereof; and,

FIG. 6 is a rear view thereof.

The broken lines shown on the medical computer are for illustrative purposes only and form no part of the claimed design.
